UNITED STATES PATENT OFFICE

152,924

DESIGN FOR A BOTTLE

Marie A. Soscie, New York, N. Y., assignor to Ricino Chemicals, Inc., New York, N. Y., a corporation of New York

Application December 4, 1947, Serial No. 142,947

Term of patent 14 years

(Cl. D58—8)

To all whom it may concern:

Be it known that I, Marie A. Soscie, a citizen of the United States, residing in the Borough of Manhattan, county and State of New York, have invented a new, original, and ornamental Design for a Bottle, of which the following is a specification, reference being had to the accompanying drawing, forming a part thereof.

I claim:

The ornamental design for a bottle, as shown.
MARIE A. SOSCIE.
